BIRDPROOFING

Julius Stanley Peles, New York, N. Y.

Application October 2, 1940, Serial No. 359,336

5 Claims. (Cl. 20—1)

This invention relates to birdproofing.

One object of the invention is to provide improved birdproofing which is adapted to prevent the alighting on the ledges of buildings of different types of birds, and especially pigeons. All birdproofing must be made in accordance with local regulations to safeguard the life and health of the birds. Oftentimes a person who is solicitous about the well being of birds may require even more stringent safeguarding of the birds and avoidance of anything which may seriously cause them any discomfort. It is therefore one object of the invention to provide birdproofing which shall meet all these requirements.

Another object of the invention is to provide birdproofing of improved construction such that it can be much more compactly packed and shipped than was heretofore possible. Since birdproofing often extends over long distances, the shipment thereof is generally a serious problem and has frequently required that the birdproofing be cut up in short sections. This in turn necessitated that a great many such relatively short sections be separately fastened to the building. The consequent increase in labor and cost of installation was very considerable especially when the birdproofing had to be secured to material of very hard composition, for example, granite or the like. It is therefore an object of the invention to overcome these drawbacks.

Another object is to provide improved birdproofing that can be readily continuously trained around corners without in any way cutting the birdproofing.

Another object of the invention is to provide birdproofing of improved collapsible structure so that it can be much more compactly shipped than even the short sections into which birdproofing had been cut as heretofore.

Another object of the invention is to provide birdproofing of an improved type whereby a long length thereof can be reliably secured in place at very few points, for example, by attachment only at the ends thereof.

Another object of the invention is to provide improved birdproofing that may be wholly free of joints so as eliminate any possibility of accidental breakage or loosening of parts and to greatly reduce the cost of manufacture.

A further object of the invention is to provide birdproofing so constructed and arranged in an improved manner as to have substantially increased efficiency in preventing birds from alighting upon the protected parts of a building or other structure.

Other objects and advantages of the invention will become apparent as the specification proceeds.

With the aforesaid objects in view, the inven-

tion consists in the novel combinations and arrangements of parts hereinafter described in their preferred embodiments, pointed out in the subjoined claims, and illustrated in the annexed drawings, wherein like parts are designated by the same reference characters throughout the several views.

In the drawings:

Figure 1 is a fragmentary view in front elevation showing a building with one form of the birdproofing applied thereto.

Fig. 2 is a view in side elevation thereof.

Fig. 3 is an enlarged perspective view of the birdproofing, illustrative of a long length thereof, but with a part removed to reduce the drawing.

Fig. 4 is a view in side elevation thereof showing the birdproofing in collapsed position.

Fig. 5 is a vertical sectional view of a modified form of the birdproofing with a separate longitudinal anchor member for spacing the turns of wire in operative mounted position.

Fig. 6 is a fragmentary view in end elevation thereof.

Fig. 7 is a similar view of a modification showing birdproofing like that of Fig. 6, but with the wire turns corrugated.

Fig. 8 is a top plan view of another modification of birdproofing.

Fig. 9 is a view in end elevation thereof.

Fig. 10 is a vertical sectional view of the birdproofing shown in Fig. 8.

Fig. 11 is a top plan view of still another modification of birdproofing.

Fig. 12 is a view in side elevation thereof showing in dot-dash lines an attaching element and the ledge to which it is secured.

Fig. 13 is a view in vertical elevation showing a modification of the invention, similar in principle to that of Fig. 3.

Figs. 14 and 15 are similar views in vertical elevation of other modifications.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawings, therefore, is submitted merely as showing the preferred exemplification of the invention.

Referring in detail to the drawings, 15 denotes a device embodying the invention. The same may comprise any building or structure 16 having an ornamental ledge 17 or the like. Mounted on this ledge is the birdproofing 20 embodying the invention. As more particularly shown in Figs. 3 to 6, the birdproofing 20 is of generally

circular or oval form, although it may also be of hexagonal or other suitable shape. As best exemplified by the circular form, the shape should be such that there would be no possible injury or discomfort to a bird attempting to alight on the ledge 17 of the building. Heretofore various structures have been provided which comprised point portions that were blunted to avoid injury to the birds. Nevertheless, in its struggle to find a foothold on the ledge, the bird would sometimes injure itself, and frequently might find lodgment between the point portions or against the side wall of the building and rest there while suffering some discomfort. With the birdproofing shown herein, it is quite impossible for a bird to rest upon the ledge because the circular form provides considerable transverse width so that birdproofing such as 20 covers substantially the entire ledge. If, however, the bird should be able to rest upon the ledge, it would suffer no discomfort, so that there will be no cause for complaint by persons who are particularly solicitous about the welfare of birds.

More particularly, the birdproofing 20 may consist of a single length of wire consisting of resilient material bent into helical form to thus provide a series of wire turns 21. The latter are arranged to lie in parallel planes and the wire consists of material that is of sufficiently good quality to afford substantially uniform extensibility throughout when the birdproofing 20 is stretched to vary the spacing between the wires 21. The birdproofing 20 also comprises means for securing the same in position and for maintaining the wire turns 21 in spaced relation to each other against the tension of the spring material. For example, the means referred to may comprise enlargements or ears 22 at the extreme ends of the wire, adapted to receive screws or other elements for securement to the building. Due to the resilient tension of the birdproofing, the same will automatically snugly hug the ledge or other part of the building to which it is affixed, and this will be true of all points intermediate of the ends 22.

In its initial position, the birdproofing 20 may be collapsed as shown in Fig. 4, with all of the turns 21 being closely side by side and in substantial contact with each other. Only the end portions 22 need project. Accordingly birdproofing which is adapted to cover a very substantial length may be shipped in a relatively small package or container. To instal the same it is merely necessary for the operator to stretch the birdproofing, preferably without exceeding its elastic limit, and to suitably anchor it to the building as at the points 22. Supplemental fastenings can be applied at an intermediate point to the base portion of one of the wire turns; such fastenings may be in the nature of ordinary hooks or staples.

The spacing between the wire turns should be sufficiently large to prevent the foot of a pigeon from straddling across and grasping two adjacent turns for thus alighting upon the birdproofing itself. Consequently the birdproofing should be stretched sufficiently to provide a spacing of approximately two inches. Otherwise it should be at a minimum in order not to permit birds to alight between the wire turns. Moreover, the diameter of the coil should exceed the length of the pigeon's leg in order that a pigeon may not be able to alight on the ledge by placing its foot between the wire turns. Consequently the di-

ameter should be approximately two and one-half inches and preferably should not exceed three inches because otherwise the birdproofing may be so large as to be visible from the street below and hence tend to disfigure the building.

In Figs. 5 and 6 is shown a modification comprising birdproofing 20a which may be substantially like that shown at 20 except that the securing means may include a relatively straight element or wire 23 having a series of recesses 24 spaced apart as hereinabove discussed. These recesses are adapted to receive the bottom turns of the different wire turns with the element 23 overlying said bottom turns. Consequently the wire turns 21 can not escape from the recesses because the bottom portions thereof lie between the element 23 and the underlying ledge. The element 23 has the advantage that it assures reliable and accurate spacing throughout without relying upon the care of the person who makes the installation. Moreover, if the extensibility of the wire is not wholly uniform throughout, the recesses 24 of the element 23 nevertheless assure a relatively uniform spacing between the turns 21. The latter are merely removably engaged with the recessed portions 24, so that for installation it is merely necessary to slip the element 23 through the birdproofing and engage it with the successive recessed portions. The element 23 may be secured in any suitable manner to the building as, for example, by enlargements or eye portions 25 adapted to receive nails or fastener elements.

In Fig. 7 is shown a modified form of birdproofing 20b which is like that shown in Figs. 5 and 6 except that the helical wire is corrugated as indicated at 26 in order to render it more difficult for birds to alight thereon. These corrugations are intended to provide small and relatively smooth curves which will not injure the bird, and they are intended to lie in the vertical planes of the wire turns in order that the effective spacing between the latter may not be reduced. Moreover, the contacts of the birdproofing in its collapsed position as shown in Fig. 4 may thus be maintained.

In Figs. 8, 9 and 10 is shown another modification comprising birdproofing 20c which embodies certain of the fundamental considerations stated for the birdproofing 20. Accordingly a series of coils or circular elements 27, and certain other similar elements 28 are provided. All of these elements lie in parallel vertical planes and are uniformly spaced from each other and are disposed along a common axis. The elements 27 are open at the bottom and terminate in hooked portions 29 which are looped around longitudinal wires 30. These wires 30 are uniformly spaced from each other and are welded to the hooked portions 29, which thus form the terminals for each of the elements 27. A relatively smaller number of elements 28 is employed, these being arranged so that the wires 30 pass over the bottom portions thereof and are welded thereto as shown in Fig. 10. The terminals or ends of the wires that form the coils 28 are welded together at 31 to thus form sections between the wires 30 and which serve to directly rigidly interconnect the same to thus provide a strong bottom structure whereby this birdproofing 20c may be anchored to a ledge or the like.

In Figs. 11 and 12 is shown still another modification of the invention comprising a birdproofing 32 which may include a ring element 33 to which are welded the inner or lower ends of a

series of wire-like fingers 34 which are upwardly and outwardly divergent from each other. The upper ends of these elements are bent over as at 35 to avoid points which might be injurious to birds. The ring element 33 is so arranged as to be adapted to receive a nail or screw 36 which may be driven into a building portion 37 for rigidly securing the birdproofing thereto. The spacing between the various fingers 34 may be readily adjusted by bending the same so as to thus obtain birdproofing effective for any particular type of bird. The birdproofing 32 is particularly adapted to be used at corners or spots where the available space is too small for the use of birdproofing such as shown at 20, although it will be appreciated that the latter may readily be trained around corners and the like. Moreover, birdproofing such as shown at 32 may advantageously be used at the extreme ends of birdproofing such as shown at 20.

Accordingly it will be perceived that I have provided a device which fulfills the objects of the invention and is well adapted for practical use.

In Fig. 13 is shown a birdproofing 40 which consists of a single wire of highly resilient material bent to provide a series of loop-like portions 41. These may be in the nature of upward and downward opening V's, the points whereof may be suitably rounded. All of these portions 41 may lie in the same plane and the structure as a whole is collapsible and expandable because of its resilience. Accordingly it may be shipped in the collapsed compact form, and then expanded to the position shown in Fig. 13 by exerting a pull thereon, and then anchoring the same to the building as by means of the ears 42. These ears are arranged of course to maintain the loops in an upright plane or at a suitable angle as may be desired.

In Figs. 14 and 15 are shown modified forms of birdproofing 43 and 44, each consisting of a series of upright loop portions forming a single wire structure, and may consist of resilient material. The loop-like portions 45 comprise rounded top portions and generally parallel sides and are arranged as a continuous one-piece structure lying in a plane, and having the end securing ears 46. In the birdproofing 44 the loop-like portions 47 are arranged in the form of inverted V's, but the structure is otherwise similar to that shown at 43, and it also terminates in the mounting ears 48. The birdproofing shown at 43 and 44 is thus maintained in an upright plane or at a desired angle by reason of its mounting and is furthermore adapted to be readily trained around any corner or other contour of a building on which the birdproofing is to be mounted. For shipment the birdproofing of the type shown at 43 and 44 may be collapsed by bending the same at one or more intermediate points, and this birdproofing may be readily unbent and straightened out when it is ready to be applied. It will be appreciated that birdproofing of the type shown at 43 and 44 can be mounted in one or more rows as may be desired to effectively cover a building ledge or the like.

I claim:

1. Birdproofing including a wire member having a series of spaced upright loop-like portions forming a resilient longitudinally expandible-collapsible one-piece structure, said portions being continuously corrugated, and means having spaced recessed portions for overlying and for

securing said wire in expanded operative position.

2. A device comprising a building and bird-proofing including a wire member having a series of spaced upright elastic loop-like portions forming a continuous one-piece structure and being bent to conform to the varying contour of the building on which the same is mounted, said member being stretched and under tension, and means at the ends of the member for securing the same to the building in upright position.

3. Pigeonproofing including a helical wire member of spring metal capable of being resiliently elongated to operative condition with the turns of wire spaced and capable of contraction so that the turns of wire lie initially closely side by side in compact condition for shipment and the like, said wire member being elongated so that the approximate spacing between the turns of wire shall be substantially greater than the initial spacing and sufficient to prevent the foot of a pigeon from grasping two adjacent turns of wire to thus perch on the pigeonproofing, means at the ends of the wire member for securing the same to a building to maintain the turns of wire in spaced parallel planes, and a base wire element for causing a precisely uniform spacing between the turns of wire irrespective of any variation in elongation at different points along the wire member, said wire element having spaced recessed portions for individually receiving base portions of the wire turns, said recessed portions being so detachably engageable with the wire turns as to permit engagement with the latter to be readily effected after the helical wire member has been stretched and secured at its ends.

4. Pigeonproofing according to claim 3 wherein in said turns of wire are provided with corrugations lying in generally parallel planes to permit contraction of the helical member with the turns of wire lying in close side-by-side position.

5. Pigeonproofing including a helical wire member of spring metal capable of being resiliently elongated to vary the spacing between the different turns of wire, said member being adapted to be longitudinally elastically contracted with the turns of wire lying closely side by side for compact packing and shipment, the spacing between the turns of helical wire being sufficient when the member is mounted to prevent the foot of a pigeon from grasping two adjacent turns of wire in order to perch on the pigeonproofing, means for securing the end portions of the helical member to the building to maintain the turns of wire in spaced parallel planes, and base means for securing said helical wire member to a supporting ledge of a building detachably, including a relatively straight wire element having spaced portions for detachably receiving base portions of the individual turns of wire as to maintain uniform the said spacing between the turns of wire against the resilient tension member, and the diameter of the turns of said member being only so large as to prevent a pigeon from reaching the ledge with its feet without being so large as to be readily visible from a street below the ledge, the turns of wire being corrugated, as and for the purpose set forth.

JULIUS STANLEY PELES.
